CERTIFICATE OF CORRECTION

PATENT NO. : D739,461 S
APPLICATION NO. : 29/456946
DATED : September 22, 2015
INVENTOR(S) : Takuya Matsumoto et al.

Page 1 of 1

It is certified that error appears in the above-identified patent and that said Letters Patent is hereby corrected as shown below:

This certificate supersedes the Certificate of Correction issued March 15, 2016. The certificate is vacated since petition to accept an unintentionally delayed priority claim under 35 U.S.C. § 120 was not filed approved by the Office of Petitions. The Certificate of Correction was published in error and should not have been issued for this patent.

Signed and Sealed this
